SAFETY RAZOR

John E. Hedlund, St. Paul, Minn., assignor of
one-half to Emma S. Leighton, Minneapolis,
Minn.

Application December 11, 1933, Serial No. 701,761

12 Claims. (Cl. 30—12)

This invention relates to new and useful improvements in safety razors of the type comprising complementary clamping members between which the blade is clamped when the razor is in use.

An object of the invention is to provide means for inseparably connecting together the various elements of a safety razor of the character herein disclosed, and whereby the blade may be supported in a position to thereby facilitate cleaning and wiping of the blade, as well as the other parts of the razor, after use.

A further object is to provide a blade retaining clip or member made from a suitable spring metal, and having formed at one end thereof an elongated link received in slots provided in the adjacent ends of the usual blade clamping members of the razor, to thereby inseparably connect together said clamping members, and said clip comprising a pair of complementary plate portions adapted to detachably receive and support a blade therebetween, and whereby the blade is guided into proper position between the clamping members, when the latter are moved into clamping engagement with the blade, and also whereby the blade is supported in substantially right angular relation to said clamping members, when the latter are in open blade-releasing position.

Other objects of the invention reside in the novel construction of the clip, whereby it may readily be detached from the clamping members, if desired; in the novel means provided in the construction of the blade retaining clip whereby, when the movable clamping member is swung out of clamping engagement with the fixed clamping member to a position substantially aligned therewith, said blade retaining clip may be conveniently actuated to release the blade by a slight downward pressure upon the outer end of the movable clamping member, and whereby the blade may be detached from the razor without directly touching it with the fingers, actuation of said clip in the above described manner also facilitating the insertion of a new blade into said clip; in the means for rotatably securing the handle to the fixed clamping member, whereby it is inseparably connected thereto and may readily be rotated in either direction to move the movable clamping member into or out of clamping engagement therewith; and, in the general construction of the blade retaining clip and the manner of attaching it to the clamping members of the razor whereby, all of the various parts of the razor are inseparably connected together, and whereby the blade is always retained in fixed

relation in said clip, whereby the clamping members may be quickly moved into clamping engagement with each other to secure the blade in position therebetween, and may as readily be detached from one another to permit cleaning and drying of the various parts of the razor, after use.

Other objects of the invention will appear from the following description and accompanying drawing and will be pointed out in the annexed claims.

In the accompanying drawing, there has been disclosed a structure designed to carry out the various objects of the invention, but it is to be understood that the invention is not confined to the exact features shown as various changes may be made within the scope of the claims which follow.

In the drawing:

Figure 1 is a sectional view substantially on the line 1—1 of Figure 2, showing the blade retaining clip connecting together the clamping members of the razor, and also showing the position of the blade, when the clamping members are in open blade-releasing positions;

Figure 2 is a plan view of Figure 1;

Figure 3 is a detail sectional view showing the clamping members in operative positions with the blade clamped therebetween;

Figure 4 is a detail sectional view on the line 4—4 of Figure 1, showing the means on the clip for receiving the razor blade; and

Figure 5 is a detail sectional view on the line 5—5 of Figure 4, showing the means provided in the complementary plate portions of the clip for preventing relative movement of the blade with respect thereto.

In the selected embodiment of the invention here shown, there is illustrated in Figure 1, for purposes of disclosure, a safety razor comprising a fixed clamping member 2, to which is rotatably secured a handle 3 having a flange 4, shown seated in a recess 5 in the clamping member 2, and retained therein by a suitable retaining member 6, secured to the clamping member 2 by suitable means, not shown. The clamping member 2 has an aperture 7 therein axially aligned with a threaded socket 8, provided in the handle 3, as best shown in Figure 1. The clamping member 2 is shown provided in its upper face with a longitudinally extending groove 9, and on its opposite sides with the usual guard fingers 11 common in safety razors of this general character.

A movable clamping member 12 is shown provided with a threaded stud 13 adapted to be re-

ceived in the aperture 7 and threaded socket 8 of the handle, as shown in Figure 3, whereby the two clamping members may be actuated to clampingly engage and secure the usual razor blade 14 therebetween. The movable clamping member 12 is shown provided at one end with a longitudinal rib 15 adapted to be received in the groove 9 in the fixed clamping member 2. The rib 15 is adapted to traverse the usual opening 16 provided in the blade, to thereby prevent the blade from relatively shifting its position, when positioned between the clamping members 2 and 12. The blade is also shown provided with an enlarged opening 17 at its center for receiving the stud 13.

At the opposite side of the rib 15, there is provided a relatively shorter rib or tongue 18 adapted to traverse the slot 16 in the blade, as will readily be understood by reference to Figure 3. A shallow recess 19 is shown provided in a movable clamping member 12 between the end of the relatively shorter rib or tongue 18 and the right hand end of the clamping member, when viewed as shown in Figure 1. The shallow recess is for clearance purposes, as will subsequently be set forth.

An outstanding feature of this invention resides in the novel means provided for inseparably connecting together the two clamping members 2 and 12, and also for retaining the blade in proper position with respect to said members. The means for thus inseparably securing together the various parts of the razor will hereinafter be referred to as the blade retaining clip, and is generally designated by the numeral 21. This clip is shown formed from flat spring metal, and is formed at one end with an enlarged link portion 22 which preferably is substantially rectangular in configuration, as best shown in Figures 1 and 2, and has its walls received in suitable slots 23 and 24, provided in the adjacent ends of the clamping members 2 and 12, respectively, as best shown in Figure 1.

The end walls 25 of the enlarged portion 22 of the clip, are provided with shoulders 26 adapted to be engaged by the lower faces of the clamping members 2 and 12, when in the positions shown in Figure 1, whereby the upper portions of said clamping members within the confines of the link portion 22, will engage the upper walls of said link portion, when viewed as shown in Figure 1, and thereby support the two clamping members in substantially the longitudinally aligned positions shown in Figure 1.

The link portion 22 of the clip 21 is provided at one side with complementary plate portions 27 and 28 between which the razor blade 14 is clamped by the spring action inherent in the metal from which the clip is constructed. The plate portion 28 is shown provided with an elongated opening or slot 29 adapted to receive an elongated rib 31, shown integrally formed in the plate portion 27 by offsetting a portion of the metal thereof. This rib 31 is adapted to traverse the slot 16 of the blade 14 in a manner similar to the rib 15 on the movable clamping member 12, whereby the blade 14 is retained in fixed relation with respect to the clip 21.

The clip 21 is so constructed and arranged with respect to the clamping members 2 and 12, that when the movable clamping member 12 is moved out of clamping engagement with the blade, and is swung to the open position, the clip will assume substantially the position shown in Figure 1, whereby it is to be noted that the

blade is supported in substantially right angular relation to the clamping members 2 and 12. When thus supported, the blade and also the clamping members 2 and 12, may readily be cleaned and thoroughly wiped after using, without having to detach the blade from the retaining clip 21. It is also to be noted that all of the various parts of the razor remain intact, and therefore cannot accidentally be mislaid or become lost, as frequently happens when the various parts of the razor must be detached from one another to enable the user to clean the razor after shaving.

The plate member 28 of the clip 21 is shown relatively longer than the plate portion 27, and is provided at one end with an open end slot or notch 32 adapted to receive the relatively shorter rib 18 of the clamping member 12, as shown in Figure 3, to thereby prevent lateral movement of the plate portions 27 and 28, when in operative positions, as shown in Figure 3. When the clamping members 2 and 12 are in operative positions, as shown in Figure 3, it will be noted that the plate portion 27 of the clip is seated in the recess 19 provided in the clamping member 12, whereby the clamping members may be actuated to firmly clamp the razor blade therebetween, its entire length. When the clamping members are in operative position, the link portion 22 of the clip 21 will assume substantially the position 30 shown in said figure.

To insert a new blade into the clip 21, the razor is preferably supported in an upright position, as shown in Figure 1, and a slight downward pressure is then applied to the outer end of the movable clamping member 12, as indicated at A in Figure 1, whereby the complementary plate portions 27 and 28 of the clip are separated because of the clamping members 2 and 12 being engaged with the end walls 25 and shoulders 26 of the 40 clips, as hereinbefore described. The new blade is then inserted between the plate portions 27 and 28 and the pressure released from the clamping members 12, whereby the plate portions 27 and 28 will clampingly secure the blade in position 45 therebetween so that when the clamping member 12 is moved into the position shown in Figure 3, the clip will accurately guide the blade into position between the clamping members whereby the stud 13 of the clamping member 12 may readily pass through the enlarged opening 17 in the razor blade, and through the opening 7 in the fixed clamping member 2 to be received in the threaded socket 8 of the handle 3. To detach the blade from the clip, it is only necessary to 50 apply a slight downward pressure upon the outer end of the movable clamping member 12, as hereinbefore stated, whereupon the complementary plate portions 27 and 28 of the clip are separated, to thereby permit the blade to drop by gravity 55 from between said members. If desired, the clip may readily be detached from the clamping members 2 and 12 by simply spreading apart the complementary plate portions 27 and 28 thereof, to permit the cross bars 33 and 34 of the clamp- 60 members to pass therebetween.

I claim as my invention:

1. In a safety razor, a pair of clamping members adapted to support a razor blade, a blade retaining member inseparably connecting together said clamping members and supporting said blade in substantially right angular relation to said clamping members, when the latter are in open, blade-releasing positions, and means by which said blade retaining member may be 70

operated to release the blade by manipulation of said clamping members.

2. In a safety razor, a pair of clamping members adapted to support a razor blade, a blade retaining clip inseparably connecting together said clamping members and having complementary portions adapted to detachably receive one end of a razor blade and guide it into position between said clamping members, when the latter are moved into clamping engagement with each other, said blade retaining clip supporting the blade in angular relation to said clamping members, when the latter are in open, blade-releasing positions, and means on one of said clamping members whereby a slight downward pressure thereon will cause the release of the blade from said clip.

3. In a safety razor, a fixed clamping member having a handle rotatably secured thereto, a movable clamping member adapted to be clampingly engaged with said fixed clamping member by rotation of said handle, thereby to secure a razor blade in position between said members, a blade retaining clip inseparably connecting together said clamping members and comprising complementary spring-actuated plate portions cooperating to receive and secure a razor blade therebetween, and whereby the blade is supported in angular relation to said clamping members, when the latter are in open, blade-releasing positions, and means whereby said spring actuated plate portions may be actuated to release the blade by manipulation of said clamping members.

4. In a safety razor, a fixed clamping member having a handle rotatably secured thereto, a movable clamping member adapted to be clampingly engaged with said fixed clamping member by rotation of said handle, thereby to secure a razor blade in position between said members, and a blade retaining clip inseparably connecting together said clamping members and comprising complementary plate portions cooperating to receive and secure a razor blade therebetween, said clip being adapted to support said clamping members in substantially longitudinal alinement, when said members are in open, blade-releasing positions, and whereby the razor blade will be supported in angular relation to said clamping members to facilitate cleaning and drying.

5. In a safety razor, a fixed clamping member having a handle rotatably secured thereto, a movable clamping member adapted to be clampingly engaged with said fixed clamping member by rotation of said handle, whereby to clamp a razor blade between said members, a blade retaining clip, means at the adjacent ends of said clamping members for receiving said blade retaining clip and whereby said members are inseparably connected, said clip comprising complementary plate portions adapted for interlocking engagement and cooperating to removably support a blade therebetween, and means whereby relative movement of one of said clamping members will actuate the complementary plate portions of said clip to thereby facilitate inserting a razor blade therebetween or removing one therefrom.

6. In a safety razor, a fixed clamping member, a handle having one end rotatably supported in said clamping member, a movable clamping member adapted to be clampingly engaged with said fixed clamping member by rotation of said handle, whereby to clamp a razor blade between said members, a blade retaining clip pivotally connecting together adjacent ends of said clamping members, said clip comprising complementary plate

portions adapted to receive and secure a blade therebetween, whereby the blade is supported in substantially right angular relation to said clamping members, when the latter are in blade-releasing positions, and means whereby the complementary plate portions of said retaining clip may be opened by the application of pressure to one of said clamping members to thereby permit the insertion of a razor blade therebetween, or the removal of one therefrom.

7. In a safety razor, a fixed clamping member having a handle mounted for movement therein, a movable clamping member having means engageable with said handle whereby a razor blade may be clamped between said members by relatively moving said handle in one direction, movement of the handle in the opposite direction releasing the blade, a blade retaining clip having a link at one end for pivotally connecting together adjacent ends of said clamping members, and said link having cooperating jaws extending laterally from one side thereof adapted to detachably receive a razor blade, and whereby when the clamping members are in open, blade-releasing positions, the blade is supported entirely by said clip and extends outwardly from said clamping members, whereby it may readily be cleaned and dried without disassembling the razor or removing the blade therefrom.

8. In a safety razor, a fixed clamping member having a handle mounted for movement therein, a movable clamping member having means engageable with said handle whereby a razor blade may be clamped between said members by relatively moving said handle in one direction, movement of the handle in the opposite direction releasing the blade, a blade retaining clip having a rectangular link portion for inseparably connecting together adjacent ends of said clamping members, said rectangular link portion having cooperating jaws extending laterally from one side thereof and adapted to removably receive a razor blade, and whereby when the clamping members are in open, blade releasing positions, the blade is supported entirely by said clip, and means on said link portion adapted to be engaged by one of said clamping members, whereby when the latter are in open, blade-releasing positions, and pressure is applied thereto, said jaws will open to permit the insertion of a blade therebetween, or the removal of one therefrom.

9. In a safety razor, a fixed clamping member having a handle rotatably connected thereto, a movable clamping member having means engageable with said handle whereby a razor blade may be clamped between said members by relatively rotating said handle in one direction, rotation of the handle in the opposite direction releasing the blade, a blade retaining clip provided at one end with a rectangular portion forming a link for inseparably connecting together adjacent ends of said clamping members, said rectangular link portion having cooperating plate portions extending laterally from one side thereof and adapted to removably receive a razor blade therebetween, whereby when the clamping members are in open, blade-releasing positions, the blade is supported entirely by said clip, and shoulders on the end walls of said link portion adapted to be engaged by said clamping members, whereby when the latter are in open, blade-releasing positions, and a slight pressure is exerted against said movable clamping member, said clip will release its grip upon the razor blade and thereby permit its removal therefrom.

10. In a safety razor, a fixed clamping member having a handle mounted for rotation thereon and inseparably connected thereto, a movable clamping member having means engageable with said handle whereby a razor blade may be clamped between said members by relatively rotating said handle in one direction, rotation of the handle in the opposite direction releasing the blade, the adjacent ends of said clamping members having apertures formed therein, a blade retaining clip provided at one end with a rectangular portion forming a link received in said apertures and thereby pivotally and inseparably connecting together said clamping members, said rectangular link portion having cooperating plate portions extending laterally from one side thereof and adapted to removably receive a razor blade therebetween, whereby when the clamping members are in open, blade-releasing positions, the blade is supported entirely by said clip, and shoulders on the end walls of said link adapted to be engaged by said clamping members, whereby when the latter are in open blade-releasing positions, and a slight pressure is exerted against said movable clamping member, the cooperating plate portions of said clip will separate to receive a blade or to permit the removal of one therefrom.

11. A safety razor comprising a pair of clamping members adapted to support a razor blade, a link inseparably connecting together said clamping members, complementary jaws on said link engageable with the razor blade to prevent the latter from accidentally becoming detached from the razor, when the clamping members are operated to release the blade, and means whereby said complementary jaws may be operated to release the razor blade, by the application of pressure to one of said clamping members. 10

12. A safety razor comprising a pair of clamping members, means for actuating said members to secure a razor blade therebetween, an element inseparably connecting together said clamping members, complementary jaws on said element engageable with one end of the razor blade to thereby prevent the latter from accidentally becoming detached from the razor, when the clamping members are operated to release the blade, 20 and means on one of said clamping members engageable with means on said element, whereby said complementary jaws may be operated to release the razor blade by the application of pressure to one of said clamping members. 25

JOHN E. HEDLUND.
